 sachusetts

Application February 19, 1947, Serial No. 729,468

7 Claims. (Cl. 134—57)

1

This invention relates to improvements in dish-washing apparatus and more particularly to such apparatus in which oppositely directed wash sprays impinge from opposite sides upon dishes held in a rack or the like which may be removably supported between the spray pipes or nozzles. Such apparatus customarily has additional rinse sprays for directing rinse water over the dishes subsequent to a predetermined period of operation of the wash sprays.

Heretofore, dish-washing apparatus of the general type to which the invention relates have had oppositely disposed spray pipes or nozzles for directing wash sprays simultaneously from above and from below against dishes held in a rack between the upper and lower spray pipes. In the prior apparatus, the opposed sprays, supplied from a common pressure supply conduit, cannot effectually utilize the total available pressure because that total pressure must be divided between the upper and the lower sprays. Also, with the upper and lower wash sprays opposing each other, there is a tendency for the sprays to neutralize each other at the region where the dishes are located and such pressure or force as the individual sprays initially may have had for dislodging food particles from the dishes may be diminished considerably before the wash water comes into washing and food-dislodging contact with the dishes.

It is among the objects of our present invention to provide a dish-washing apparatus wherein upper and lower wash sprays have alternating operation so that the total available pressure of the wash water is utilized alternately for the upper and the lower sprays, and so that the full pressure of the individual sprays is effective for cleaning dishes without diminution by opposing sprays. We have found that a definitely greater efficiency of cleansing action is attained by directing forceful washing sprays alternately in one direction and then in the opposite direction, as compared with prior dish-washing procedures. If food particles are only partially dislodged by the operation of the sprays in one direction, a subsequent agitation thereof by the oppositely directed sprays completes the dislodgment, whereas in prior apparatus such particles frequently are lodged at neutralized spray regions and fail of being dislodged.

Another object is to provide a dish-washing apparatus wherein there are upper and lower oppositely directed wash water spray pipes of which only the upper sprays, for example, operate for a predetermined period of time in response to

5 manual actuation of a starting mechanism, and then the upper sprays automatically stop and only the lower sprays operate for a predetermined period of time, followed again automatically by operation only of the upper sprays, and so on for a predetermined number of alternations of the sprays and ultimate stopping of both the upper and the lower wash sprays.

A further object is to provide a dish-washing apparatus having upper and lower oppositely directed wash water sprays alternating automatically through a predetermined wash cycle and then adapted automatically to stop, and having upper and lower oppositely directed rinse water sprays which may be manually or automatically operable from above and below the dishes following stopping of the wash sprays.

A still further object is to provide a dish-washing apparatus having spray means for directing 20 hot water on dishes held in a spray chamber and including means for inducing outflow from the chamber of moisture-laden air and inflow of relatively dry and cool air which is rapidly circulated in drying relation to the dishes subsequent to a 25 wash cycle of the apparatus and prior to opening of the spray chamber for removal of the dishes.

Another object is to provide a dish-washing apparatus wherein upper and lower wash sprays operate alternately and wherein rinse sprays operate automatically at the end of the wash cycle and are separately operable independently of a wash cycle.

Yet another object is to provide a dish-washing apparatus wherein the wash water is more effectively rid of food particles prior to its re-circulation through the wash water spray pipes, as compared with prior comparable dish-washing apparatus.

It is, moreover, our purpose and object generally to improve the structure and efficiency of dish-washing apparatus and more especially such apparatus having upper and lower oppositely directed wash water sprays.

In the accompanying drawings:

45 Fig. 1 is a front elevation of dish-washing apparatus embodying features of the invention, portions of the housing walls being broken away to show more clearly the interior parts;

50 Fig. 2 is a side elevation of the apparatus of Fig. 1;

Fig. 3 is a detail cross-sectional view of the wash water control valve, on a larger scale;

Fig. 4 is an elevation of the valve of Fig. 3, 55 showing its operating connections;

2

3

Fig. 5 is a diagrammatic view of the piping and electrical connections; and

Fig. 6 is a fragmentary cross-sectional detail showing the passage for air inflow past the lower portion of the closure when the latter is closed.

Referring to the drawings, upper and lower horizontally disposed wash water spray pipes are indicated at 10 and 12 respectively. The upper spray pipes 10 are supported by and connected to the horizontal manifold pipe 14 while the lower spray pipes 12 are similarly supported by and connected to the horizontal manifold pipe 16. Both of the horizontal manifold pipes 14, 16 are connected to the vertical supply pipe 18 whose lower end is connected to the pump 20 which may be belt driven as at 22 from the electric motor 24.

The spray pipes 10, 12 and their supply pipes 14, 16 and 18 are all enclosed within a generally rectangular housing indicated generally at 26 which defines a chamber 27 within which dishes to be washed may be suitably arranged and supported. One wall of the chamber 27 conveniently may be provided with a transparent panel 28 opposite the region where the washing takes place, which is between the upper and lower spray pipes 10, 12, so that action interiorly of the housing may be observed. Also, an access opening 30 in the side wall of housing 26 may be closed by any suitable openable closure which, as shown, is a vertically slidable panel 32. If desired, a similar slidable panel 34 may be provided in the opposite side wall of the housing. The dishes preferably are arranged in a suitable rack (not shown) which may be inserted in chamber 27 through the access opening 30.

As best seen in Fig. 1, the housing 26 has the inclined bottom wall 35 extending a substantial distance laterally and slightly downwardly from one side wall to the other. Short of the vertical plane of the right hand side wall of the main housing 26, this bottom wall 35 joins the vertical wall 36 which constitutes a side wall of a return chamber 38 which projects substantially beyond the vertical plane of the right hand side wall of the main housing 26 and which is open into the interior of the main housing at 40.

Return chamber 38 is suitably mounted on a base 42 and constitutes a support for the main housing 26 above. Legs 44 extend between the bottom wall 35 and base 42 for supporting the left hand side portion of the main housing in vertically spaced relation to base 42, as seen in Fig. 1. Legs 44 support the base 42.

The pump 20 conveniently is located in the space between bottom wall 35 and base 42, to one side of vertical wall 36. It is shown primarily supported at 46 on base 42, with its inlet 48 connected to the return chamber 38 and its outlet 50 connected to the lower end of the vertical supply pipe 18. The electric motor 24, for driving the pump, also may be supported on base 42, in the space between the base 42 and bottom wall 35 of main housing 26.

According to the invention, a wash water flow control valve indicated generally at 52, is located at the juncture of the lower horizontal wash manifold pipe 16 with the vertical supply pipe 18. As represented in the showing of Figs. 3 and 4, valve 52 is rotatable to connect vertical supply pipe 18 to the upper wash manifold pipe 14, in which position it cuts off flow from vertical pipe 18 to the lower wash manifold pipe 16, and to connect the supply end of vertical supply pipe 18 to the lower wash manifold pipe 16, in which po-

4

sition it cuts off flow in vertical pipe 18, beyond the valve, to the upper wash manifold pipe 14.

Alternating rotation of valve 52, first in one direction and then in the opposite direction, is accomplished by the reciprocations of a piston 54 in a cylinder 56 which is reciprocated by fluid under pressure delivered into cylinder 56 first on one side of the piston and then on the other side. As herein shown, the cylinder 56 is connected to the building hot water supply system, the pipe 58 being a leader from such a system and extending vertically within main housing 26 with its open lower end preferably disposed below the access opening 30, for supplying hot wash water to the lower portions of the housing, especially to the return chamber 38, it being understood that soap or the like is added to the wash water as may be desired. A manual valve 60 in pipe 58 will be closed excepting when the housing is being supplied with wash water.

A pipe 62 leads from pipe 58 on the supply side of manual valve 60 and has a four-way valve 64 therein for passing water under pressure through conduit 66 to cylinder 56 on the upper side of piston 54 while the cylinder at the lower side of the piston is connected through conduit 68, valve 64 and conduit 70 to vertical pipe 58 on the apparatus side of manual valve 60, or for passing water under pressure through pipe 68 to cylinder 56 on the lower side of piston 54 while the cylinder at the upper side of the piston is connected through pipe 66, valve 64 and pipe 70 to vertical pipe 58, as before. Hence, when pressure liquid is acting at one side of piston 54 to drive it in one direction in cylinder 56, the cylinder at the other side of the piston is connected for exhaust of liquid into the housing of the apparatus.

Piston 54 has a piston rod 72 depending through the lower end of cylinder 56, with link connection at 74 to an arm 76 which is rigid with the rotatable element of wash water supply control valve 52. When the piston is driven in one direction, valve 52 is operated to connect only the upper wash spray pipes 10 for discharge, and when the piston is driven in the opposite direction, valve 52 is operated to connect only the lower wash spray pipes 12 for discharge.

It is a feature of the invention that the upper and the lower wash water sprays operate alternately. For example, the upper and lower wash sprays may operate alternately with the upper sprays on for six seconds, and then off for six seconds and with the lower sprays off for six seconds while the upper sprays are on, and on for six seconds while the upper sprays are off. A washing cycle may extend through sixty seconds, for example, with the upper sprays on five times for six second operations during the cycle and with the lower sprays similarly on five times for six second operations during the cycle, although the time period of operation and the number of operations per cycle may be varied as desired.

As hereinbefore described, the reciprocations of piston 54 operate the wash water supply control valve 52 to attain alternating operation of the upper and lower wash sprays 10, 12, and operation of the four-way valve 64 effects the reciprocation of the piston. The automatic control and timing of these mechanisms, according to the present disclosure, enables the automatic performance of a predetermined wash cycle in response to mere depression of a button. However,

a predetermined cycle of alterations of the upper and lower wash sprays may be initiated and maintained in any desired manner and by any means, and it should be understood that the electric control as illustrated is merely exemplary.

As herein shown, a cam shaft 78 may be mounted at any convenient location, such as on the top wall 29 of the main housing. The cam shaft is driven through gears 80 by a small electric motor 82 which may be a 2 R. P. M. motor, for example, so that the cam shaft, through gears 80, makes one complete revolution in seventy-six seconds, for example. However, for a purpose which later will appear, the disclosed embodiment of the invention includes a clutch 79 for the cam shaft, and the clutch is disengaged excepting when the motor 82 is energized. Hence, when the motor 82 is de-energized, the cam shaft 78 is disconnected from its motor drive and is free to be rotated independently of the motor and the gears 80.

Clutch 79 may be operated by a solenoid 81 whose coil is connected (Fig. 5) to the circuit of motor 82 so as to be energized whenever the motor is energized. Solenoid 81 has its armature 83 spring actuated in one direction and connected to the pivoted clutch-actuating lever 85. When the solenoid 81 is energized, its armature is actuated in opposition to its spring to engage the clutch, and the clutch continues engaged so long as motor 82 is in operation. Hence, the cam shaft 78 is rotated whenever motor 82 operates but is disconnected from the motor as soon as the motor stops. This latter is important in that it is desirable to re-set the cam shaft to a predetermined starting position following each complete or partial rotation thereof. For this purpose, a spring 87 has one end anchored and its other end connected to the cam shaft 78 or to some element rigid with the cam shaft, so that, as the cam shaft is rotated in one direction by the motor 82, energy is stored in the spring which restores the cam shaft to its starting position, determined by stop pin 89, as soon as the clutch 79 is disengaged when motor 82 stops.

The cam shaft 78 has a cam 84 fixed thereon with a high part which may have approximately 272 degrees of extent around the periphery of the cam, for maintaining a switch arm 86 closed during slightly more than three quarters of a revolution of the cam, representing a time period of sixty seconds, for example. The switch arm 86, when closed, completes an electric circuit through the pump motor 24 and maintains the pump 20 in operation until the switch arm 86 drops to the low part of cam 84 at the end of sixty seconds, which is the predetermined duration of the wash cycle in the illustrated embodiment.

Another cam 88, fixed on cam shaft 78, controls a switch arm 90 which is held closed throughout almost a complete revolution of the cam, there being only a short low part on the cam to which the switch arm 90 drops at the end of each complete revolution. Switch arm 90, when closed, completes a holding circuit through the cam shaft motor 82 so that this motor, having been started by depression of push button switch 92, continues in operation throughout the predetermined seventy-six second complete cycle of the apparatus as herein disclosed. As soon as motor 82 is started, cam 88 closes switch arm 90 to complete the holding circuit through motor 82. Also, the cam 84 immediately closes switch arm 86 to start the pump motor 24 to keep the

pump motor operating for sixty seconds or for slightly more than three quarters of a revolution of cam shaft 78.

A third cam 94, fixed on cam shaft 78, operates a switch arm 96 which controls the solenoid 98 which shifts the four-way valve 64 for attaining alternating operation of the upper and lower wash sprays. As shown diagrammatically in Fig. 5, valve 64 may have an operating arm 100 connected to the armature 102 of the solenoid 98, with a spring 104 urging the armature to its outermost position as seen in Fig. 5 wherein the valve 64 is set in its position connecting the supply pipe 58 through pipe 62 to the pipe 66, and connecting pipe 68 to pipe 70. When solenoid 98 is energized, it draws armature 102 to the right in Fig. 5, thereby to effect a clockwise rotation of valve 64 to connect the branch supply pipe 62 to pipe 68 leading to the under side of cylinder 56 and to connect pipe 66 from the top side of the cylinder to connecting pipe 70, for exhaust. When solenoid 98 is de-energized its armature 102 returns to its position of Fig. 5, to effect a counter-clockwise rotation of valve 64 back to its position of Fig. 5.

Cam 94, as shown, has five high portions equally distributed around approximately 272 degrees of the cam, and the switch arm 96 alternately engages the high and the low portions of the cam.

In the embodiment herein represented, the cam 94 energizes solenoid 98 for five six-second periods at six second intervals during the first sixty seconds of cam rotation, so that the upper and lower wash sprays will be alternately on and off five times during the wash cycle and each on period will be of six seconds' duration and each off period excepting the final off of the cycle will be of six seconds' duration.

After the pump 20 has stopped, at the end of the sixty second wash cycle, the washed dishes are rinsed with clean hot water before being removed from the apparatus. For this purpose we provide a suitable number of upper rinse spray nozzles 106 and a similar number of lower rinse spray nozzles 108 within the chamber 27. As herein shown, all of the rinse spray nozzles are connected together for simultaneous operation, they being supplied with clean hot water under pressure through branch pipe 110 which is connected to the hot water supply pipe 58 on the pressure side of manual valve 60. However, flow to the rinse spray nozzles normally is prevented by the solenoid valve 112 in the branch pipe 110 whose solenoid 114 is energized to open valve 112 only during the final eight seconds or so of each complete cycle of the apparatus. To this end, the cam shaft 78 has a fourth cam 116 fixed thereon for controlling a switch arm 118 which opens and closes a circuit through the solenoid 114. Cam 116 has a single high portion designed to hold switch arm 118 closed only during the final eight second period of a complete revolution of cam shaft 78. Hence, during the sixty second wash cycle, solenoid 114 will be de-energized and valve 112 will be closed.

In the embodiment represented, the rinse valve 112 continues closed for eight seconds after the wash cycle is complete and is open only during the last eight seconds of a complete seventy-six second cycle of the apparatus. This eight second delay between the stopping of the wash sprays and starting of the rinse sprays allows time for the usual dripping from the wash sprays to stop, thus avoiding dripping of wash water on the dishes after they have been rinsed, which would objectionably spot the

dishes. At the end of the rinse cycle the switch arm 118 drops to the low part of cam 116 to de-energize solenoid 114, and switch arm 90 drops to the low portion of cam 88 to stop the cam shaft motor 82, and the apparatus stops in readiness for commencement of a new cycle after the washed dishes have been removed and another rack of dishes to be washed has been inserted in chamber 27. The new cycle may be initiated as before by merely depressing button switch 92.

It is usual to maintain the wash water in dish-washing machines at a temperature around 140° F., and to have the temperature of the rinse water in the neighborhood of 190° F. Notwithstanding that these temperatures are somewhat below the boiling temperature of the water, there nevertheless is a considerable amount of vaporization of the hot water and, in the absence of preventive measures, the hot vapor confined within the machine has constantly increasing pressure which, when released by opening the wash chamber closure 32, would rush out much in the manner of a gust of steam. According to the invention the moisture-laden air is exhausted from chamber 27 before the closure 32 is opened. A fan 120 is provided in a flue conduit 122 which latter opens into the chamber 27. As herein shown, the fan 120 is connected for operation whenever a main switch 124 is closed, excepting during the wash cycle.

It is important to note, however, that provision is made for inflow of relatively dry and cool air to take the place of the hot moisture-laden air being exhausted through flue conduit 122. As best seen in Fig. 6, there is an opening 126 past the lower margin of closure 32, and exterior air streams into chamber 27 whenever fan 120 is operating, and the incoming relatively dry and cool air flows between and around the dishes in the chamber. Hence fan 120 not only rids chamber 27 of objectionable moisture-laden hot air prior to opening of closure 32, but induces inflow of air which dries or partially dries the dishes prior to opening of the closure 32.

In Fig. 5, there is represented one effective embodiment of electrical control means whereby operation of the fan is controlled and whereby the described wash cycle of alternate operations of the upper and lower wash sprays may be followed by operation of the rinse sprays. As shown, the cam-controlled operation of the switch arm 86, for controlling the pump motor 24, acts through a relay 128 which initially is energized by a momentary manual depression of button switch 92. Relay 128 has the three movable contacts 129, 130, 131, of which the contact 130 closes a circuit through the pump motor 24, and contact 131 closes a circuit through the cam-shaft motor 82 and clutch relay 81 in response to energization of relay 128. Relay contact 129 also closes in response to energization of relay 128 and completes a holding circuit through relay 128 after switch arm 86 has been closed by cam 84. The initial closing of a circuit through cam-shaft motor 82 and clutch relay 81 starts rotation of cam shaft 78 whose cam 84 immediately closes switch arm 86 to complete the holding circuit through relay 128 and this circuit continues closed throughout the wash cycle and then opens to de-energize relay 128 when switch arm 86 drops to the low part of cam 84, with consequent opening of the circuit through pump motor 24.

The initial rotation of cam shaft 78 also effects closing of switch arm 90 by the holding cam 88, thereby to complete a holding circuit through

cam-shaft motor 82 and clutch relay 81 independently of relay 128, and this latter holding circuit is maintained closed through a complete wash and rinse cycle of the machine or throughout substantially a complete rotation of holding cam 88.

Contact 131 of relay 128 upon de-energization of the relay, closes a circuit through the motor of fan 120 so that the fan will be operating at all times, when main switch 124 is closed, excepting during the wash cycle.

The cam 94 which, as previously explained, effects five six-second energizations of relay 98 at six-second intervals, to provide the alternating operation of the upper and lower wash sprays, is effective only so long as the relay 128 continues energized. The rinse cam 116, on the other hand, can close a circuit through the solenoid 114 of the rinse valve 112 independently of the relay 128, and does so close a circuit during the final eight seconds of each complete wash and rinse cycle of the machine, at which time the relay 128 is de-energized.

It frequently is desirable to operate the rinse sprays independently of any wash cycle. For example, glassware may be washed by other means than the present apparatus, and it may be desired to only rinse the glassware in the present apparatus. According to the invention such an independent rinsing may be effected by merely

closing a rinse button switch 132, assuming that main switch 124 is closed. A fifth cam 134 on cam shaft 78 actuates switch arm 136 which controls a holding circuit through a rinse control relay 138 and energization of cam shaft motor 82. Closing of switch 132 energizes relay 138 which causes closing of the movable contacts 140, 142 and 144 of the relay. Closing of relay contact 140 completes a circuit through cam shaft motor 82 and clutch relay 81 which promptly rotates cam shaft 78. Closing of relay contact 142 conditions a holding circuit for relay 138 so that the holding circuit is completed through the relay as soon as cam 134 rotates to close its switch arm 136, and the relay continues energized until the switch arm 136 drops to the low portion of cam 134. Closing of relay contact 144 energizes the rinse valve control relay 114 to start the rinse sprays 106, 108 which continue on so long as the control relay 138 is energized. The single high portion of cam 134 may be adapted to hold cam switch arm 136 closed for an eight second rinsing period, at the end of which switch arm 136 will drop to the low portion of cam 134 to de-energize relay 138, and opening of relay contacts 140, 144 de-energizes motor 82 and rinse solenoid 114. The cam 134 may be similar to cam 116 but has its high portion at the start of a rotation while the high portion of cam 116 is at the end of a rotation. Excepting when control relay 138 is energized, the closing of switch arm 136 by cam 134 has no effect, as during the operation of the apparatus for a washing followed by a rinsing.

After a separate rinsing operation, the spring 87 acts to re-set the cam shaft 78 as soon as clutch 79 disengages following de-energizing of motor 82 and solenoid 81. Also, a push-button stop switch 145 is provided by which the operation of the apparatus may be stopped at any stage of a wash or rinse cycle, in which case the said spring 87 resets the cam shaft.

The cam shaft 78, its motor 82, all of the cam switch arms and the relays 81, 128, 138 may be mounted as a unit in a suitable casing 146 as indicated in Fig. 1, with the push buttons 92, 134

and 145, and main switch 124, accessible at the front of the apparatus.

It will be apparent from the foregoing that the invention provides an extremely efficient dish-washing apparatus which, as shown, goes through a complete cycle in response to mere depression of button 92, including a sixty second wash cycle and an eight second rinse cycle. During the wash cycle, the dishes are subjected to the forceful action of the wash sprays alternately, from above and from below the dishes in chamber 27, with the upper sprays operating at full pressure for six second periods at six second intervals, and with the lower sprays similarly operating during the intervals when the upper sprays are off. This full pressure alternating operation of the wash sprays attains a definitely greater washing efficiency as compared with the prior practice of splitting the available pressure between simultaneously operating upper and lower wash sprays. Also the invention avoids any neutralizing of the agitating effect of the sprays, with each series of sprays acting entirely separately and uninfluenced by the opposed series of sprays. What food particles may not be entirely dislodged by the sprays operating with full force in one direction will be removed by the following sprays operating with full force in the opposite direction.

After the wash sprays have accomplished their work during sixty seconds of a complete cycle of the apparatus, the rinse sprays, above and below the dishes, operate simultaneously for eight seconds to thoroughly rinse the dishes prior to their removal at the end of the complete cycle.

Whenever desired, rinsing may be effected independently of a wash cycle by merely closing the rinse button switch 132 to initiate a rinse cycle of eight seconds duration, for example.

Any suitable strainer 148 may be provided in the return chamber 38 within which may be suspended a suitable bag 150 of fabric or the like, for collecting food particles and other foreign matter from the water returning to the return chamber 38. A removable drain board 152 directs the returning water into the bag 150 which latter is of a sort to be thrown away when it has collected such a quantity of foreign matter that water cannot pass freely through the bag and strainer for re-circulation by pump 20. This ensures against food particles and the like being in the re-circulated wash water.

While we have disclosed an embodiment of the invention wherein the control is entirely electric, it should be understood that other means may be employed to initiate a wash cycle of alternately operating wash sprays operating alternately from above and below the dishes to be washed. Also, any suitable means, manual or automatic, may be employed for initiating a predetermined period of operation of rinse sprays after a wash cycle has been completed, or independently of a wash cycle.

We claim as our invention:

1. In a dish-washing apparatus, upper and lower wash water spray conduits substantially oppositely disposed in spaced horizontal planes, the upper spray conduits having spray outlets opening toward the lower spray conduits and the lower spray conduits having spray outlets opening toward the upper spray conduits, whereby both the upper and lower sprays are directed across substantially the same region but in generally opposite directions, a pump having conduit connection to the said spray conduits for

delivering wash water to said spray conduits, flow control means in said connection movable to one position in which the pump output is directed only to the upper spray conduits and movable to another position in which the pump output is directed only to the lower spray conduits, means for driving said pump, and mechanism responsive to operation of said pump driving means for quickly shifting said flow control means intermittently between its two said positions, thereby to maintain substantially continuous sprays of wash water at full pump pressure across said region but with the said sprays directed across said region alternately in generally opposite directions.

2. In a dish-washing apparatus, upper and lower wash water spray conduits substantially oppositely disposed in spaced horizontal planes, the upper spray conduits having spray outlets opening toward the lower spray conduits and the lower spray conduits having spray outlets opening toward the upper spray conduits whereby both the upper and lower sprays are directed across substantially the same region but in generally opposite directions, a pump conduit connection to the said spray conduits for delivering wash water to said spray conduits, flow control means in said connection movable to one position in which the pump output is directed only to the upper spray conduits and movable to another position in which the pump output is directed only to the lower spray conduits, means for driving said pump, mechanism responsive to starting of said pump driving means for maintaining the pump in operation for a predetermined wash period and for automatically stopping it at the end of the wash period, said mechanism including means connected to said flow control means and operative to quickly shift said means from one of its said positions to the other alternately at predetermined intervals during the said wash period of operation of the pump thereby to provide substantially continuous wash water sprays downwardly and upwardly in said region alternately from said upper and lower spray conduits throughout said predetermined wash period of operation of the pump.

3. In a dish-washing apparatus, upper and lower generally horizontally disposed wash water spray means in opposed relationship, and upper and lower rinse water spray means, said wash water spray means and said rinse water spray means being located and adapted to direct their sprays in substantially the same region, means for supplying wash water under pressure to said wash water spray means, means for supplying rinse water under pressure to said rinse water spray means, flow-control means for the wash water supply operative in one position to direct the wash water at full pressure only to the upper wash water spray means, and operative in another position to direct the wash water at full pressure only to the lower wash water spray means, means for quickly shifting the said positions of the flow-control means a predetermined number of times at predetermined time intervals during a predetermined wash period of operation of the apparatus thereby to provide substantially continuous spraying throughout the wash period but with the upper and lower spray means operating alternately, and means for opening the rinse water supply means automatically after a predetermined interval following the wash period thereby to start the rinse water sprays only after the said interval within which dripping

11

from the upper wash water spray means will have stopped.

4. In a dish-washing apparatus, upper and lower wash water spray conduits arranged in generally horizontally opposed relationship, and upper and lower rinse water spray conduits arranged and adapted to discharge their sprays generally in the same region in which the wash sprays discharge, a pump connected to the wash water spray conduits for supplying wash water thereto at a predetermined pressure, a rinse water supply conduit connected to the rinse water spray conduits for supplying rinse water thereto at a predetermined pressure, a valve controlling the water supply to the rinse water spray conduits, a wash water control valve between the said pump and the upper and lower wash water spray conduits and operative in one position to direct the full pump output to the upper wash water spray conduits and operative in another position to direct the full pump output to the lower wash water spray conduits, means for starting and stopping the pump, and means responsive to the rinse water supply pressure for automatically quickly shifting said wash water control valve alternately and at intervals from one of its said positions to the other whenever said pump is operating.

5. In a dish-washing apparatus having upper and lower wash water spray conduits in generally horizontal opposed relation and adapted to direct sprays of wash water generally in the same area but in opposite directions, upper and lower rinse water spray conduits arranged and adapted to direct sprays of rinse water in opposite directions generally in the same area in which the wash sprays are directed, the combination therewith of means for supplying wash water to the upper wash water sprays a predetermined number of times at predetermined intervals and for supplying wash water to the lower wash water sprays substantially throughout the said intervals when the upper wash water spray conduits are not being supplied, and means operative only after the wash sprays have stopped for supplying rinse water to the upper and lower rinse water spray conduits simultaneously thereby to provide oppositely directed simultaneous upper and lower rinse sprays in the same region previously traversed by the alternating upper and lower wash sprays.

6. In a dish-washing apparatus, upper and lower wash water spray pipes in generally horizontal opposed relation and adapted to direct sprays of wash water generally in the same area but in opposite directions, and upper and lower rinse water spray nozzles arranged and adapted to direct sprays of rinse water in opposite directions generally in the same area in which the wash sprays are directed, a pump for delivering wash water to said wash water spray pipes, a wash water control valve operative in one position to direct the full pump output only to the upper wash water spray pipes and operative in another position to direct the full pump output only to the lower wash water spray pipes, means for driving the pump for a predetermined wash period and for stopping it at the end of the period, means operative only during said wash period for quickly shifting said wash water control valve between its said positions a prede-

12

termined number of times at predetermined intervals during said wash period thereby to provide substantially continuous wash sprays throughout the wash period with the upper and lower sprays discharging alternately, and means for supplying rinse water to both the upper and lower rinse water spray nozzles simultaneously and automatically only at the end of a predetermined drip period following said wash period.

7. In a dish-washing apparatus having upper and lower wash water spray pipes in generally horizontal opposed relation and adapted to direct sprays of wash water generally in the same area but in opposite directions, and upper and lower rinse water spray nozzles arranged and adapted to direct sprays of rinse water in opposite directions generally in the same area in which the wash sprays are directed, a chamber below said spray pipes and nozzles for holding a supply of wash water, a hot water pressure supply conduit for supplying hot rinse water to said upper and lower spray nozzles and for replenishing the supply of wash water in said chamber, manual means in said conduit for controlling the replenishing of said chamber, electrically operated means for controlling the supply of rinse water to said spray nozzles, a pump for delivering wash water from said chamber to said wash water spray pipes, electrically operated means for driving the pump, including means for stopping it at the end of a predetermined period of operation, a valve operative in one position to direct all of the pump output only to the upper wash water spray pipes and operative in another position to direct all of the pump output to only the lower wash water spray pipes, means including a cylinder and pressure-actuated piston for alternating the positions of said valve a predetermined number of times automatically at predetermined intervals during said period of operation of the pump, and means operative following stopping of the pump for opening said rinse water control means for a predetermined period following stopping of the pump.

JOHN J. McDONALD.
